ABSTRACT: A laundry drier includes a drum which is mounted for rotation in two opposite directions. A plurality of elongated flexible lines are secured to the drum at axially spaced points and arranged to be wound onto the drum when it rotates in one direction and to be unwound when it rotates in the opposite direction. A biasing spring permanently urges the drum to rotate in the direction in which it winds up the lines. Arresting means is operable for arresting the drum from rotation in the direction unwinding the lines and actuating means is located axially adjacent one end of the drum and has limited freedom of movement axially of the drum between a first position in which it engages the drum for rotating the same, and a second position in which it is disengaged from the drum.

LAUNDRY DRIER

BACKGROUND OF THE INVENTION

The present invention relates generally to laundry driers, and more particularly to the type of laundry drier provided with one or more lines which may be extended for hanging laundry thereon for drying purposes.

Laundry driers of this type are already known. They suffer, however, from various disadvantages including their rather complicated construction, the correspondingly expensive manufacture and assembly, and the susceptibility to mechanical malfunction which inevitably results in a complicated construction. Furthermore, the arresting arrangements provided in these prior art constructions are complicated and not entirely reliable. Such arresting arrangements in these constructions may arrest the line when it is desired to withdraw it from the device, and on the other hand, it may release the line when pull is exerted on it by laundry which has been hung on the line.

SUMMARY OF THE INVENTION

It is, accordingly, an object of the present invention to provide a laundry drier of the type mentioned above which is not subject to the aforementioned disadvantages.

A further object of the invention is to provide such a laundry drier which is simple in its construction and therefore inexpensive to manufacture.

An additional object of the invention is to provide such a laundry drier which is free from malfunctions and which requires no maintenance.

A concomitant object of the invention is to provide such a laundry drier which is provided with reliably operating arresting means.

In pursuance of the above objects and others which will become apparent hereafter, one feature of the invention resides in the provision of the device of the type under discussion which comprises a drum mounted for rotation in a first and an opposite second direction, and at least one elongated flexible line which is secured to the drum and is arranged to be wound onto the latter when the drum rotates in the first direction and to be unwound when the drum rotates in the second direction. Biasing means is associated with the drum and permanently urges the same for rotation in the first direction. Arresting means is operable for arresting the drum front rotation in the second direction. Actuating means is arranged axially adjacent one end of the drum and has limited freedom of movement axially of the latter between a first position in which it engages the drum for rotating the same, and a second position in which it is disengaged from the drum.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a longitudinal section through one embodiment of the invention;

FIG. 2 is a section taken on the line II—II of FIG. 1;

FIG. 3 is a section taken on the line III—III of FIG. 1;

FIG. 4 is a front view of a component element of the device shown in FIG. 1;

FIG. 5 is a longitudinal section, partly broken away, through a device according to our invention and illustrating a second embodiment; and

FIG. 6 is a view similar to FIG. 5 but illustrating still another embodiment of the invention.

DESCRIPTION OF THE PREFERRED EMBODIMENTS

Discussing now the drawing in detail, and firstly the embodiment illustrated in FIGS. 1-4 thereof, it will be seen that the device in toto is identified with reference numeral 10. It comprises at its opposite axial ends two end plates 11 and 12 whose rearward portions 13 and 14 are angled in outward direction. The purpose of this is to secure the device 10 to a support, such as a wall or the like, via the portions 13 and 14.

5 10 These portions are provided with openings 15, as illustrated in FIG. 4, through which securing or mounting elements can be extended to be secured in the support, and it will be appreciated that the openings 15 may be of any desired configuration, for example keyhole shaped.

15 15 A tubular support 18 is provided which is rigidly connected with the end plates 11 which for this purpose are provided with central openings 16 and 17, respectively, from whose circumference the projections 19 and 20 extend substantially radially through cutouts 21 provided in the support 18 and to prevent the same from rotation and from axial shifting relative to the end plates 11 and 12.

20 20 As shown in FIG. 1, a helical spring 22 surrounds the support 18 and has one end extended through a cutout 23 in the support 18 so as to be connected with the latter. The other end 25 of the spring 22 is connected to a projection 24 of a coupling member 25 of substantially cup-shaped configuration so that the spring is prevented from rotating with reference to the coupling member 25. Parenthetically, it should be mentioned that the spring could of course be of other than helical configuration.

30 30 The coupling member 25 is provided with a collar 26 with which it is turnably mounted on the support 18; it further has an outwardly extended region 17 which accommodates one 35 end of a drum 28 onto which the one or more elongated lines are to be wound. A further element 29, corresponding substantially to the coupling element 25 and also turnably mounted on the support 18, is connected with the opposite end of the drum 28. The elements 25 and 29 are connected 40 with the drum 28 in such a manner as to rotate therewith but not relative thereto. This is in the illustrated embodiment of FIGS. 1-4 accomplished by screws 30 which extend through the drum 28 and into tapped bores of the elements 25 and 29, these bores not being specifically illustrated. However, it is to 45 be understood that other connections are possible, for instance press-fitted connections or the like. Evidently, the member 29 could also be configurated in a different manner, if desired and this will be evident to those skilled in the art.

50 50 In the illustrated embodiment of plurality of elongated lines 31, which may consist of any suitable material such as rope, synthetic plastic material or the like, are to be wound onto the drum 28. Their inner ends are connected to the drum 28 via lugs 32 portions of which extend through slots into the drum 28 and are connected thereto by screws 33. The opposite or 55 free ends of the lines 31 are passed through holes in an elongated pull bar 34, as clearly shown in FIG. 2, and are secured therein by knotting, as also seen in FIG. 2. It should be pointed out that only a single one of the lines 31 is illustrated in the drawing, but this is done for the sake of clarity and several such lines are provided in the illustrated embodiment.

60 60 The coupling element 25 has a radially extending peripheral portion 35 abutting against the end plate 11 and is provided with cutouts 36 which are arranged in identical spacing from the support 18 and into which a coupling portion 37 which is rigid with a handle 38, can selectively be extended. The handle 38, on the other hand, is turnably mounted via a pin 38 or shaft 39 which extends into the support 18. As illustrated particularly in FIG. 1, the shaft 39 is provided with a longitudinally extending recess 40 one end of which merges with a circumferentially extending recess annulus 41. The projection 19 provided on the end plate 11 extends into the annular recess 41 the latter being so dimensioned that the shaft 39 and the handle 38 are shiftable axially of the drum 28 through a 70 predetermined distance. The purpose of the elongated recess 75

40 is to permit the introduction of shaft 39 to the the tubular support 18 beyond the projection 19. In the illustrated embodiment the handle 38 and the shaft 39 are of one piece, advantageously consisting of synthetic plastic material.

As particularly shown in FIG. 3, a collar 42 is provided on the handle 38 and extends in direction towards the end plate 11, being provided with an interior annulus of teeth 43. A pawl 44 is mounted at the exterior side of the end plate 11 turnably via the bolt 45, and the turning movement of the pawl 44 in the direction towards the annulus of teeth 43 that is limited by an abutment 45' in such a manner that the engagement of the pawl with the teeth is just possible to the extent that it can reliably prevent rotation of the handle 38 when such engagement has taken place. The end plate 11 is provided with a curved slot 46 which can register with the cutouts 36 of the coupling element 25 and which is at its middle region enlarged. The coupling portion 37 of the handle 38 extends through the curved slot 46 and, when the handle 38 is moved to its axially inner position, the coupling portion 37 also extends into one of the cutouts 36 of the coupling element 25. When the handle 38 is axially withdrawn to its axially outer position, the coupling portion 37 does not extend into any of the cutouts 36 of the coupling element 25, but still extends into the curved slot 46. This is clearly shown in FIGS. 2 and 3.

When the handle 38 is withdrawn to its axially outer position, it is no longer coupled with the drum 28 so that the lines 31 can be withdrawn from the latter by exerting pull on the pull bar 34. This results in tensioning of the spring 22 because of the fact that the opposite ends thereof are respectively coupled with the support 18 and the drum 28. When the lines 31 have been withdrawn to the desired extent, the pull bar 34 may be connected to a suitable support, such as a wall or the like, via a handle portion 47 (compare FIG. 2) which is retractable into the pull bar.

When this has taken place, and it should be understood that it can take place because the handle 38 is moved to its axially outer position in which at the same time the annulus of teeth 43 is so far spaced from the pawl 43 that they do not engage, the handle 38 is turned in a sense in which the lines are further unwound until the end position is reached which is determined by cooperation of the coupling portion 37 and the curved slot 46. Thereupon, the handle 38 is moved to its axially inner position so that the coupling portion 37 also extends through one of the cutouts 36 in the coupling element 25 whereupon the handle 38 is turned in opposite direction, that is in a sense winding the lines 31 onto the drum 28 until the lines have been tensioned to the desired extent. As this turning movement takes place the annulus of teeth 43 moves below the pawl 44 in a sense in which there is no engagement between the two. Once the desired tensioning of the lines 31 has been obtained with this, turning of the handle 38 in a sense in which the lines 31 could be again unwound from the drum 28 is prevented by the fact that in the axially inner position of the handle 38 the pawl 44 cooperated with the teeth of the annulus 43. Thus, the device will maintain the lines 31 tightened as desired. It will be appreciated from the drawing that the arrangement of the pawl 44 below the opening 16 is such that when the device is properly arranged in the manner in which it is intended to be used, the free end of the pawl 44 will cooperate with the teeth of the annulus 43.

While the lines 31 are to be rewound onto the drum 28, the handle 38 is axially shifted to its axially outer position, whereby the cooperation between the pawl 44 and the teeth of the annulus 43 is interrupted, while simultaneously the cooperation between the handle 38 and the drum 28 via the coupling element 25 is terminated. This permits the spring 22 to rotate the drum 28 in a sense winding the lines 31 back onto the drum 28.

A housing is provided consisting of shell sections 48 and 49 which serve to protect the components of the device located between the end plates 11 and 12. The shell sections 48 and 49 extend from one to the other of the end plates 11 and 12 and are secured thereto in suitable manner which is not

specifically illustrated. The rear side of the housing, that is the side which will normally face a support on which the device is to be secured, is substantially open and covered only by angled marginal portions 50 and 51 of the shell sections 48 and

5 49. The drawing shows that the marginal portion 50 of the upper shell section 48 is downwardly and outwardly inclined and that the marginal portions 51 of the lower shell section 49 approximately parallels the inclination of the marginal portion 50 whereby, as clearly shown in FIG. 2, the moisture running off the other side of the housing is prevented from running into the interior of the housing.

As also shown in FIG. 2, the front side of the device, that is the side at which the line or lines are extended, is provided with a recess for accommodating the pull bar 34. The recess is

15 identified with reference numeral 52 and the end plates 11 and 12 are provided with two lugs 53 and 54 constituted by portions of the end plates 11 and 12 which are cutouts cut or stamped out and bent inwardly at a substantially right angle, as shown. The lugs are located one behind the other and spaced

20 from one another at a distance corresponding to the breadth of the pull bar 34. The foremost lugs 53 are so dimensioned and arranged that when the pull bar 34 is located in the recess 52, they are located substantially in the plane of its outer face, whereas the rearmost lugs 54 are longer and serve as abutments for the pull bar 34. The arrangement of the shell sections 48 and 49 is such, as illustrated in the drawing, that no moisture can enter into the housing through or in the region of the recess 52 either.

25 Caps 55 and 56 of nonoxidizable material, such as synthetic plastic material or the like, serve to cover the end plates 11 and 12. As the drawing shows, the cap 55 is provided with an opening through which the annulus 42 of the member 38 can just pass, and is provided with an outwardly extending collar

30 57 which extends beyond the annulus 42 to the outside. The collar 57 may also serve to guide the handle 28, if necessary and desired. The second cap, the one identified with reference numeral 56, is not so apertured. The caps 55 and 56 can be secured in suitable manner to the end plates 11 and 12, for instance by screw threads or the like to the end plates. Recesses

35 58 are provide in the caps 55 and 56 in those edge portions thereof which face the lugs 13 and 14 of the end plates 11 and 12 and which embrace projections 59 provided on these lugs so as to afford proper alignment and quick assembly.

30 Coming, finally, to the embodiments illustrated in FIGS. 5 and 6, and more particularly that of FIG. 5, it will be seen that the embodiment of FIG. 5 is in most respects similar to that of FIGS. 1-4, with identical reference numerals identifying identical components. It is emphasized that certain portions

40 are omitted, that is those portions that are shown in FIG. 1 at the left-hand side thereof, because they are identical with the ones shown in FIG. 1. The embodiment in FIG. 5 differs, as will be seen, from that of FIG. 1 in that the pin 60 shown herein is provided with an elongated annular recess 61

45 bounded by annular shoulders 62 and 63. The recess 61 straddles a tubular portion 64 which is stationarily mounted in the member 65 and which is shorter than the length of the recess 61 to permit axial shifting of the pin 60 and the handle 38 associated with it. Axial movement of the handle 38 is limited by

50 cooperation of the tubular portion 64 with the annular shoulder 63 where axial withdrawal of the handle 38 is concerned. Beyond the annular shoulder 63 the pin 60 conically tapers towards its end, as shown. The pin 60 is hollow and provided with a longitudinal slot 66 extending inwardly from its

55 end and approximately to the middle of the recess 61. The pin 60 in this embodiment consists of springy material which makes possible its introduction into the member 65 even if the tubular portion 64 is stationarily mounted previously, because when the pin 60 is inserted, the ribs 67 are inwardly deflected

60 to the diameter of the tubular portion 64 when they engage, on introduction of the pin 60, the conical surfaces 68 provided for this purpose. A withdrawal of the pin 60, on the other hand, is precluded—insofar as unintentional withdrawal is

65 concerned—by cooperation with the annular shoulder 63 with the juxtaposed end face of the tubular portion 64.

70

75

70 to the diameter of the tubular portion 64 when they engage, on introduction of the pin 60, the conical surfaces 68 provided for this purpose. A withdrawal of the pin 60, on the other hand, is precluded—insofar as unintentional withdrawal is concerned—by cooperation with the annular shoulder 63 with the juxtaposed end face of the tubular portion 64.

The embodiment of FIG. 6, finally, differs from the preceding embodiments in that the diameter of the pin 71 associated with the handle 38 corresponds substantially to the outer diameter of the member 70 corresponding to the member 65 in FIG. 5. In the end regions the member 70 is provided with radially projecting hooks 72 which extend into longitudinal slots 73 provided on the member 70. The pin 71 is hollow, as in the embodiment of FIG. 5, and provided with one or more slots 74 extending inwardly from its end and making possible an elastic deflection in the region of the hooks 72. This makes it possible to introduce the pin 71 into the member 70 without any difficulty. As soon as the regions of the pin 71 which are provided with the hooks and elastically inwardly bent on such introduction, perched therewith the longitudinal slots 73 of the member 70, these regions of the pin 71 return to their original undeformed condition of the springy characteristic of the material of the pin 71 so that the hooks 72 engage in the slots 73. The latter are longer than the hooks 72 which makes possible the withdrawal of the pin 71 together with the handle 38 until the hooks 72 abut against the edge faces bounding the ends of the slots 73.

It should be emphasized that the illustrated embodiments are by way of example only and are not to be considered limiting in any sense. It is clear that modifications may be made and such modifications will offer themselves readily to those skilled in the art. By way of explanation, it might be pointed out that the handle may be separate from the associated pin and secured thereto in releasable manner, rather than being of one piece therewith. Also, other modifications are possible, such as use of one or more spiral springs in place of a helical springs, in the replacement of the tubular support member with individual support members for opposite ends of the device which are respectively associated with one of the plates and wherein each such individual support member serves to turnably support one end of the drum, only one support member having to be hollow to accommodate the pin of the respective handle. It should again be emphasized that other modifications are possible beyond those which have been indicated here.

It will be understood that each of the elements described above, or two or more together, may also find a useful application in other types of constructions differing from the types described above.

It will be understood that each of the elements described as embodied in a laundry drier, it is not intended to be limited to the details shown, since various modifications and structural changes may be made without departing in any way from the spirit of the present invention.

What is claimed as new and desired to be protected by Letters Patent is set forth in the appended claims:

1. A device of the character described, particularly a laundry drier, comprising in combination, a drum mounted for rotation in a first and an opposite second direction and including tubular support means supporting said drum for such rotation; at least one elongated flexible line secured to said drum and arranged to be wound onto the latter when said drum rotates in said first direction, and to be unwound when said drum rotates in said second direction; biasing means permanently urging said drum for rotation in said first direction;

actuating means arranged axially adjacent one end of said drum for rotating the same; arresting means for arresting said drum against rotation in said second direction; and cooperating abutment means provided on said support means and said actuating means, said abutment means including abutment portions provided on said support means and spread resiliently compressible hook portions provided on said actuating means and arranged to cooperatively engage with said abutment portions and at least limit displacement of said actuating means with reference to said drum.

2. A device as defined in claim 1, said actuating means being movable to and from a position engaging said drum for rotation, and said drum and said actuating means being provided with cooperating coupling portions arranged to interengage with each other when said actuating means is moved to said position.

3. A device as defined in claim 1, said biasing means including a helical spring coaxial with said drum and having an end portion rigid with the same.

20 4. A device as defined in claim 1, said support means being provided with slots into which said hook portions extend and which constitute said abutment portions.

5. A device as defined in claim 1, said actuating means having a shaft mounted for turning movement coaxially with said drum and shiftable axially relative thereto, said shaft being provided in its periphery with an axially elongated recess; and further comprising a projection on said drum extending into said recess for limiting the extent of movement of said actuating means.

30 6. A device as defined in claim 5, said drum including an end plate extending transversely to its axis and provided with said recess, and said recess including an elongated first portion and an annular second portion merging with one end of said first portion.

35 7. A device as defined in claim 5, said actuating means further including a handle adapted to be gripped by the fingers of a user, and said handle being rigid with said shaft.

8. A device as defined in claim 7, said handle being of one piece with said shaft.

40 9. A device as defined in claim 1; further comprising a housing mounting said drum for rotation; and wherein said arresting means includes at least one first arresting portion provided on said actuating means of one piece therewith, and at least one second arresting portion provided on said housing, at least one of said arresting portions being movable with reference to the other into and out of arresting engagement with the same.

45 10. A device as defined in claim 9, said first arresting portion being configurated as an internal annulus of teeth, and said second arresting portion comprising a pawl arranged to cooperate with the teeth of said annulus.

50 11. A device as defined in claim 10; and further comprising an abutment associated with said pawl for limiting the movements thereof.

55 12. A device as defined in claim 1, said line having a free end portion; and further comprising a pull bar secured to said free end portion arranged to be gripped by a user for exerting pull on said line to thereby unwind the same from said drum by effecting rotation of the latter in said second direction in response to such a pull.
